GIRDLE

Mack Kahn, Cedarhurst, N. Y., assignor to Artistic Foundations, Inc., New York, N. Y., a corporation of New York

Application December 11, 1952, Serial No. 22,628

Term of patent 3½ years

(Cl. D20—2)

To all whom it may concern:

Be it known that I, Mack Kahn, a citizen of the United States, residing at Cedarhurst, in the county of Nassau and State of New York, have invented a new, original, and ornamental Design for a Girdle, of which the following is a specification, reference being had to the accompanying drawing, forming part thereof.

In the drawing:

Fig. 1 is a front elevational view of a girdle, showing my new design;

Fig. 2 is a side elevational view thereof; and
Fig. 3 is a rear elevational view thereof.

I claim:

The ornamental design for a girdle, substantially as shown.

MACK KAHN.
